UNITED STATES PATENT OFFICE.

ROBERT HILLSON, OF ALBANY, NEW YORK.

IMPROVEMENT IN STOVE-PIPE DAMPERS.

Specification forming part of Letters Patent No. 123,171, dated January 30, 1872.

To all whom it may concern:

Be it known that I, ROBERT HILLSON, of the city and county of Albany, State of New York, have invented a new and Improved Damper for Stove-Pipes, Smoke-Stacks, and the like; and I do hereby declare that the following is a description thereof, reference being had to the accompanying drawing forming a part of this specification, in which—

Figure 1 represents a side view of the damper embodying my invention. Fig. 2 is a longitudinal cross-section of the same. Fig. 3 is a transverse sectional view. Fig. 4 is a cross-sectional view, taken at line No. 1 in Fig. 1.

My invention relates to the combination of a serrated or sinuated edge with the body of the damper, and also the arrangement of one or more induction-ports with the spindle of a hollow damper; and also the arrangement of a series of discharge-ports with the periphery of the same, whereby the air from without the pipe can be introduced within the damper to be discharged within the pipe, and the whole be made to operate more effectually to regulate the draught of the stove or furnace.

To enable others skilled in the art to make and use my invention, I will proceed to describe it in reference to the drawing and the letters of reference marked thereon, the same letters indicating like parts.

In the drawing, A represents the damper, which consists of the two plates A' A', each constructed with a plane concave central section, a a, surrounded by a plane section, a' a', as shown in Figs. 1, 2, and 3, and so arranged that the plane surfaces of the sections a' a' will be at a little distance apart while there will be a considerably larger cavity central in the damper, as shown in Fig. 3. I also make with the said double plano-concave space between the shells A' A' the duct B, which duct leads from one side of the damper to the central cavity, as shown in Figs. 1 and 2, and is intended to receive and conduct the air passing through the induction-ports attached to the cut-off valve made with the operating stem of the damper. On the periphery of the damper I make a serrated edge, e e e, as shown in Fig. 1, which serrations are intended to nearly or quite touch the inner surface of the pipe when the damper is turned horizontal; a sinuated

edge could, if desired, be used as an equivalent, and either form of edge would operate to effect an equal distribution of the current or draught from the center of the pipe to the outer portion of its space or bore when the damper is turned to check the said draught. On the periphery of the damper and between the bases of the serrations I make the several discharge-ports x x x, Fig. 1, which discharge-ports communicate with the space between the shells A' A' and the interior of the pipe to discharge the air received into the interior of the damper out between the serrations e e e in the pipe. The damper is swung on the stem C from the pintle d, working in one side of the pipe, and the bearing surfaces e e e of the cut-off valve working in the opposite side of the pipe, as shown in Figs. 1 and 2, which stem is provided with a thumb-piece, D, by which it is operated. One end of the stem C is provided with a cut-off, E, which cut-off consists of the closing end piece f and the several bearing pieces e e e radiating out from the stem C, as shown in Fig. 4, and the band g inclosing a portion of the apparatus between the bearings e' e', as shown in Figs. 1 and 2. The length of the stem C from the end piece f to the pintle d is longer than the diameter of the pipe by about one inch, more or less, on a six-inch pipe. Attached to the pipe on the shut-off side is a circular collar, F, into which the closing end piece f can be made to enter. The stem C and its attached cut-off are capable of being pushed or drawn in either direction to the limit afforded by the increased length of the stem over the diameter of the pipe, and, when pushed in direction indicated by dotted arrows in Figs. 1 and 2, the closing end piece will enter the recess of the collar F and close the end, to prevent the entrance of the air within the damper from without the pipe, but when the stem is drawn out, as shown in Figs. 1 and 2, the shut-off will be opened so as to admit the air from the outside of the pipe to the interior of the damper to be discharged through the ports x x x, at the periphery of the damper into the pipe in a direction indicated by arrows in the several figures.

The manner in which the several parts of this invention operates is as follows: The damper is swung central within the pipe or

smoke-stack P, in the manner above described, and is capable of being turned vertically within the same, as shown in Fig. 1, when the draught of the pipe will be uncheck'd, (provided the cut-off valve is thrown forward to cause the end piece f to enter the recess of the collar F, as shown by dotted lines in Fig. 2; or the damper can be turned so as to spread hori-

1. The arrangement of the serrated edge c c or equivalent situated edge with the damper A, whereby a checked draught will be equally distributed at the periphery of the damper to escape upward in close contact with the inner surface of the pipe, substantially as and for the purpose set forth.

2. The damper A, provided with the central

as shown by dotted lines in Fig. 2; or the end piece f to enter the recess of the collar F, cut-off valve is thrown forward to cause the end piece f to enter the recess of the collar F, whereby a checked draught will be equally distributed at the periphery of the damper to escape upward in close contact with the inner surface of the pipe, substantially as and for the purpose set forth.

1. The arrangement of the serrated edge c c or equivalent situated edge with the damper A, whereby a checked draught will be equally distributed at the periphery of the damper to escape upward in close contact with the inner surface of the pipe, substantially as and for the purpose set forth.

2. The damper A, provided with the central
